(Cl. D81—4)

To all whom it may concern:

Be it known that we, Henri Desguin and Nestor Sauvage, citizens of Belgium, residing respectively at Koekelberg (Belgium), and 3 rue des Combattants, Berchem-Ste-Agathe (Belgium), have invented a new, original, and ornamental Design for a Gas Stove, of which the following is a specification, reference being had to the accompanying drawing, forming a part hereof.

Figure 1 is a front perspective view of a gas stove embodying our new design, and

Figure 2 is a side view thereof.

The side not shown of the gas stove is like the side shown.

We claim:

The ornamental design for a gas stove, as shown and described.

HENRI DESGUIN.
NESTOR SAUVAGE.
